(57) **CLAIM**

The ornamental design for a spectrophotometer, as shown and described.

DESCRIPTION

FIG. 1 is a top perspective view of a spectrophotometer showing our design;

FIG. 2 is a front view of the spectrophotometer of FIG. 1;
FIG. 3 is a back view of the spectrophotometer of FIG. 1;
FIG. 4 is a left side view of the spectrophotometer of FIG. 1;
FIG. 5 is a right side view of the spectrophotometer of FIG. 1;
FIG. 6 is a top view of the spectrophotometer of FIG. 1; and,
FIG. 7 is a bottom view of the spectrophotometer of FIG. 1.
The dashed lines shown in FIGS. 1-7 form no part of the
claimed design.
